United States Patent Office.

MELCHER MELLINGER, OF DAYTON, OHIO.

Letters Patent No. 60,768, dated January 1, 1867.

IMPROVEMENT IN CANE STRIPPER.

The Schedule referred to in these Letters Patent and making part of the same.

TO ALL WHOM IT MAY CONCERN:

Be it known that I, MELCHER MELLINGER, of Dayton, in the county of Montgomery, and State of Ohio, have invented a new and improved Cane Stripper; and I do hereby declare that the following is a full, clear, and exact description thereof, which will enable others skilled in the art to make and use the same, reference being had to the accompanying drawings, forming part of this specification, in which—

Figure 1 is a plan or top view of my invention.

Figure 2 is a front elevation of the stripping device.

Figure 3 is a section taken on the line $x x$, fig. 1.

Similar letters of reference indicate like parts.

My invention consists in the employment of two or more spring cutters, which, with a stationary plate, form the device for cutting off the heads of the canes; and, with the further addition of a self-adjusting plate or plates, form the stripping device, the whole being constructed, arranged, and operating as will be presently described.

A A B designate the three sides of a triangular frame, which is supported by legs a , in the proper manner. Across the frame are placed slots, C C C, upon which the canes are placed. D is a stationary blade, whose shank is secured to the inner face of the part B of the frame. This blade is of an A form, and points upward, and its edges are shaped as usual. On each side of the blade D there is arranged a spring blade, E. Each blade E has a bevelled edge facing the blade D, and is cut away at the lower end of the edges to form a shoulder guide, i , which coincides with similar shoulders, correspondingly, on the stationary blade. These shoulders guide the blades E in their expansion and contraction, and each blade E terminates in a spring, b , which is carried down and bent around a screw or the like, driven in the frame B, and then bent upward and fastened to another screw, C, or the like, as shown clearly in fig. 2. This construction of the shank of the blade forms a spring blade, which has a continual tendency to press inward the blade D, but which may be thrown away from it by pressing the cane down between the blades D and E so that it may reach the socket or opening, F, for stripping it. G G are spring plates, having grooved tops, as shown at e, fig. 2. These are carried around under the part B of the frame, and secured to the other side thereof. Each has a slot, f, cut in it, which works on a pin or screw, g, secured in the part B. Thus these three plates are allowed an up and down play, so that they may adjust themselves to the size of the cane being stripped. In using the cane stripper, the heads can first be cut off by shoving the canes down between the blades D E, after which the canes are to be inserted in the opening F, and drawn through in the usual manner.

What I claim as new, and desire to secure by Letters Patent, is—

The shoulders i , in stationary blade D, and spring blades E, operating in combination with the slotted spring blades G, as and for the purpose specified.

The above specification of my invention signed by me this 22d day of May, 1866.
